UNITED STATES PATENT OFFICE.

WILLIAM E. UESCHEL, OF VALPARAISO, INDIANA.

STRING-BEAN GRADER.

1,295,642.

Specification of Letters Patent. Patented Feb. 25, 1919.

Application filed January 8, 1919. Serial No. 270,229.

To all whom it may concern:

Be it known that I, WILLIAM E. UESCHEL, a citizen of the United States, residing in Valparaiso, Porter county, Indiana, have invented a new and useful Improvement in String-Bean Graders, of which the following is a specification.

The object of my invention is to produce a string bean grader to sort the beans into the different sizes required by canneries. Such sorting or grading of string beans takes no account of the length of the bean but only of its thickness and the grading is effected by having opposing gaging surfaces in the grader from slots sufficiently long to freely permit all beans to pass therethrough lengthwise and exactly broad enough to just permit the thickness or belly of the bean of the desired grade to pass therethrough crosswise or transversely and to stop from passage all larger beans.

Heretofore such green bean graders as have come into use have been of the reciprocating or so-called end-shake variety. The purely mechanical objections to all such reciprocating apparatuses are well known and need not be recited. But in addition it also happens that such existing graders do their work with a rough approximation only so that the beans, after they have been graded, are run over picking tables where such beans as are off-size are picked from the body of the mass. It results, therefore, that the accuracy of the grading produced by the present string bean graders really depends upon the sight and judgment of human operators and is not, therefore, mechanically accurate.

Now I have devised a string bean grader which is rotary, in fact cylindrical, in form and which thus does away with the objectionable features of reciprocating mechanisms and which grades the beans with such nicety that subsequent hand sorting is not essential. What is more my construction enables me to use gaging slots which run circumferentially, in planes more or less transverse to the cylinder axis, so as to permit gravity to pull the bean through a

gaging slot not merely in the bottom of the 50 cylinder but also for a considerable way up on the sides.

The construction of my grader is simple and readily understood. It comprises in its illustrated form two interlaced cylinders 55 each composed of a plurality of members, generally mounted eccentrically with respect to each other and both supported on the same rotary travelers. The juxtaposition of the members of these interlaced cages 60 is such that the faces of the members of one cylinder form with the opposing faces of the members of the other interlaced cylinder a large number of longitudinal, more or less transverse gaging slots running around the 65 cylinder in various planes. What is more although these slots are arranged to be of the exact gaging size in the lower half of the cylinder, the arrangement causes one of the cages to be displaced with reference to 70 the other in the upper half of the cylinder, so as to displace the opposing faces with respect to each other whereby the gaging slots increase in size at the top sufficiently to form broad openings through which any beans 75 which happen to have become clogged in the slot when it was narrower, for gaging purposes, at the bottom, will fall thus automatically clear. The circumferential gaging slot at the bottom becomes a circumferential 80 releasing slot at the top.

All this will more fully appear in the annexed drawing in which:

Figure 1 is a section on the line 1—1 of Fig. 2;

Fig. 2 is a longitudinal side elevation with the top and bottom in cross-section;

Fig. 3 is a diagrammatic sectional detail to illustrate and plan of operation;

Fig. 4 shows the gaging body or casting 90 in perspective;

Figs. 5 and 5^a show details in section and perspective of the mounting of the rings on the traveler;

Fig. 6 shows a modified traveler;

Fig. 7 a modified ring;

Fig. 8 a modified bean guide and

Fig. 9 a modified gaging slot and guide.

My grader consists of two interlaced cages which I will designate respectively as the A-cage and the B-cage. The A-cage consists of two end rings A, a number of intermediate rings A² and a number of rows of castings or gage bodies A³ all held together into one rigid structure by rods and nuts A'. The B-cage consists of end rings B with circular outer faces, and intermediate rings 5 B², which may be held apart by spacing tubes B³ and which are supplied with ears B⁵. Rods B⁴ passing through apertures in the two end rings B and through apertures in the ears B⁵, clamp the whole into one 10 rigid structure.

To more fully describe the A-cage, we consider the casting or gage bodies A³, shown in perspective in Fig. 4. This consists of cross bars A³³, connecting the two 20 side wings A³² which, at the bottom, have semicylindrical rod supports A³¹. In the case shown in Fig. 1, ten of these castings are mounted in a circular row with their semi-cylinders A³¹ abutting to form complete rod 25 supports for the passage of the clamping rods A'. These ten castings form one ring or row of castings. Although I have, for the sake of greater perspicuity, shown but four of these rows of gage-bodies in Fig. 3, 30 in practice I use as many rows as may be necessary to constitute a grading cylinder of sufficient length to effect the grading with the required degree of accuracy. The rows of castings A³ are separated by annular 35 plates A² one of which lies between each two consecutive rows of castings.

The B-cage, as above pointed out, consists of two end rings B and a number of parallel intermediate rings B² all connected by the 40 tie rods B⁴, it being understood that the intermediate rings B² slide in the closely fitted slots A³⁴ in the side wings A³³ of the casting A³ and that the body of the rings B² lie exactly midway between the cross bars 45 A³³. The slots A³⁴ thus act as spacing guides for the rings B² which slide up and down in them and the faces of the rings B² taken with the opposing faces of the bars A³³ constitute in this case strictly transverse 50 gaging slots through which the beans to be graded pass. The interlaced cages are supported in a rotary fashion by having the end rings A and B' mounted on travelers or rollers R, which are driven in any suitable manner not considered necessary to show, and which are arranged so as to give a tilt to the axis of the grading cylinder.

The beans to be graded are fed into the cylinder at the left in Fig. 3. As the cylinder rotates, the beans are drawn up the side, that is upward on the left, in Fig. 1 and then tumble back toward the bottom. In this way the beans pass over the circumferential slots in one row of castings A³

and some of the beans of proper thickness 65 pass through. But the beans, in tumbling and falling, will not all drop to the bottom of the same row of castings, for some of them because of the tilt will fall across the partition A² into the next row of castings, 70 so that the mass of beans will gradually pass from the feed end, on the left in Fig. 3, to and through the discharge end of the grader, on the right in Fig. 3.

The pairs of adjacent partitions A² thus 75 constitute guides for holding the beans between them more or less transverse or circumferentially to the cylinder which alines them with the grading slots and thus more readily permits their passage therethrough. 80 As before stated, the more or less transverse or circumferential grading slots furnish an unobstructed passage for the circumferentially arranged beans at all points in the lower half of the cylinder and permits the 85 full pull of the force of gravity to become effective upon the bean and not merely a component of this force as would be the case with slots running in an axial direction in which arrangement the only really effective 90 grading slots would be those at the very bottom whose walls are vertical, for the walls of the slots along the sides of the cylinder away from the bottom would not be vertical but in inclined positions which makes these 95 slots so ineffective as to be practically useless.

In addition to having the guide rings A² for holding the beans in a more or less truly transverse direction, the longitudinal rods 100 A¹ or rather the wings A³¹ which run axially from the feed to the discharge end of the cylinder act as stirring or more accurately lifting devices for the beans. That is to say string beans which are lying in the 105 bottom of the cylinder are carried up on the left, say, of Fig. 3 by these lifting ribs to a point from which they tumble when the downward action of gravity overcomes the lifting action of the rib because of the increasing slant of the rib. These lifting devices are valuable since they produce a more rapid rearrangement and realinement of the beans with reference to the gage slots and thus increase the number of bushels handled 110 for a given size of apparatus.

The operation of grading and releasing is illustrated in Fig. 3. The rings or gaging members B² at the bottom are in a position to constitute gaging slots with the side faces of the opposing cross arms A³³. These arms are tapered at A³ so as to slide the beans toward the gaging apertures, which increases the amount of the work done. At the top of the cylinder the rings B², because of the fact that they move radially with respect to the members of cage A, are raised clear of the cross bars A³³ so that the two narrow gage 120

slots at the bottom now become one broad releasing slot at the top. It must be understood in this connection that beans of just the right size frequently get stuck in these 5 gage slots at the bottom and along the lower ends and unless they are removed, they act as an obstruction to further gaging which sharply diminishes the amount of grading done. Such obstruction is, however, completely 10 obviated by the construction which I have described.

I may also use a faceted roller R' shown in Fig. 6 instead of a round roller which would act to jostle the grading slots. My 15 grader works effectively, however, with a circular traveler.

Instead of making the rings B² in one solid piece, I may make them in a number of sections B²⁰ as shown in Fig. 7, each 20 hinged at one end to a rod B⁴, in which case instead of using only three rods B⁴, I should use a larger number of rods. The bottom hinged section would be drawn by gravity down into the same position as that 25 occupied by the bottom of the solid ring and the gaging would be the same as in the solid ring construction. At the top, I supply a stationary cam C which strikes against a wing B²¹ on the section B²⁰ to tilt this section 30 upward away from the gaging slots to convert them into releasing slots. The sectional ring construction thus produces the same relative radial movement of the members which form the slots as is effected by 35 the eccentric mounting in the construction of Fig. 1.

The rings A² form partitions between consecutive rows of castings and the only way for beans to pass from the feed to the discharge 40 end of the cylinder is to have them tumble across these partitions, this tumbling being due to the tilting of the cylinder. In order to produce a more certain feed I may, however, apply these rings so as to give 45 them, for a fraction of a turn, a bias toward the discharge end. This is clearly shown in Fig. 8. The pockets with diagonal webs are 180° apart and contain only one slot. The straight pockets contain two slots. In this 50 way, one complete turn of ring A² produces a shift of the beans toward the discharge end equal to the distance between a pair of rings A². The rings or circular members thus take in effect a spiral form which I 55 still designate under the generic name of ring.

By having the rings B² in sections, it will also be possible to have the gaging slots of Fig. 8 on an inclination to the truly transverse as shown in Fig. 9 so that the gaging bodies at each end of this inclined section will have a staggered relation to each other. All of these geometric relations I designate as circumferential, although it is to be un-

derstood the farther the gage slots get away from being accurately transverse, the less efficient they grow.

It will now be clear that, broadly considered, my grader consists of a cylinder, corresponding to the A-cage, in which are a set 70 of transverse or circumferential apertures large enough to permit an unobstructed passage for the beans, and a set of circumferentially arranged members, which register with those apertures, to narrow them to gaging size at the bottom and up the sides but which are radially movable with reference to the cylinder to cause them to withdraw sufficiently from these apertures at the top and there make them of a size sufficient to 80 release any captured beans.

I claim:

1. A string bean grader comprising the combination of a rotary cylinder supplied with circumferential apertures to permit an 85 unobstructed passage for the beans, a set of circumferentially arranged members registering with the cylinder apertures to narrow them to gaging size at the bottom and radially movable to cause their removal therefrom at the top sufficient to constitute releasing apertures, substantially as described.

2. A rotary green bean grader consisting of a rotary member provided with circumferential apertures to permit an unobstructed 95 passage for the beans and a multiplicity of relatively movable circumferential members, to transform the apertures into gaging slots, substantially as described.

3. A rotary green bean grader consisting 100 of two interlaced cylinders, each having a multiplicity of circular members, the opposing faces of which constitute gaging slots, substantially as described.

4. A rotary green bean grader having 105 circumferentially arranged gaging slots and guides for alining the beans in a circumferential direction, substantially as described.

5. A rotary green bean grader having circumferentially arranged gaging slots, circumferential guides for alining the beans and transverse lifting devices for tumbling the beans, substantially as described.

6. A rotary cylindrical string bean grader having two sets of circumferentially arranged gaging members, movable radially with respect to each other to constitute circumferential gaging slots therebetween at the bottom and releasing slots therebetween at the top substantially as described.

7. A rotary string bean grader comprising circular rows of gage bodies having guiding slots and rings moving in the slots and forming both gaging and releasing slots with the gage-bodies, substantially as described.

8. A rotary string bean grader comprising a cage composed of circular rows of

gage bodies, spacing rings and clamping rods, and an interlaced cage composed of end rings, intermediate rings and clamping rods, the intermediate rings and gage-bodies forming circumferential gaging slots, substantially as described.

In testimony whereof I have signed my

name to this specification in the presence of two subscribing witnesses.

WILLIAM E. URSCHEL.
